TOBACCO-PIPE REAMER

Paul A. Shoudy, Seattle, Wash., assignor to Kirsten Pipe Company, Seattle, Wash., a corporation of Washington

Application November 18, 1940, Serial No. 366,040

4 Claims. (Cl. 131—246)

This invention relates to a tool for use in reaming or dressing out the cake of a tobacco-bowl, and for its principal object aims to provide a device for this purpose characterized in that its reaming office is performed with noticeably less effort than heretofore and in a manner to preclude the same from "hanging up" on the cake crust with the resultant cracking of the cake which has been the objection to practically if not all tobacco-pipe reamers heretofore available.

It is a further and a particular object to devise a reaming tool having an open center and which is self-clearing in action.

It is a further and a particular object still to devise a reaming tool for tobacco-bowl use of such form and nature as to permit the same to be produced inexpensively and in consequence sold at a low figure.

Other objects and advantages, with the foregoing, will appear in the course of the following detailed description and claims, the invention consisting in certain novel features of construction and in the arrangement of parts illustrated in the accompanying drawing and hereinafter described and claimed.

In said drawing:

Figure 1 is a top plan view of a tobacco-bowl reamer embodying the features of the present invention.

Fig. 2 is a side elevation thereof.

Fig. 3 is also a side elevational view of the reamer modified in that the same is given an approximate 60° twist and shown in its application to the bowl of a Kirsten-type pipe; and

Fig. 4 is a horizontal section taken to an enlarged scale on line 4—4 of Fig. 3, the view being somewhat diagrammatic to show the working of the tool.

Having reference to said drawing it will be seen that the reamer is produced from a blank of sheet metal suitably die-cut and turned about a shaping mandrel to the general form of a truncated cone modified in that the two ends 5—6 of the blank each recede inwardly somewhat from a true concentric. It is of course apparent that the blank might as well be die-cut and turned to the suggestion of a paraboloid in such instances as the same is produced for use with pipes having curved rather than the illustrated straight-sided bowl chambers.

Intended to function, respectively, as the leading and trailing parts of the tool, the former of the two ends 5—6 is given a terminal deflection by striking the same outwardly to an

angle of approximately 45° and this deflected lip, denoted by 5', acts as the reaming edge of the device. Such lip is desirably paralleled by the trailing edge 6' of the tool, from which the same is spaced to define a clearing throat therebetween, and is characterized in that the same develops a shear-scrape as the tool is given a twist by the application of finger pressure, this shear being obtained through the instrumentality of locating the lip on a line describing a receding steep helix.

In applying said finger pressure the same is exerted through an integral tab-like ear 7 extending upwardly from the reamer proper at a point immediately to the rear of the reaming lip and in a plane approximately tangent to the tool's upper perimeter.

The manner of the tool's usage should be obvious from the foregoing description taken with the illustration of the now preferred embodiment, noting particularly the diagrammatic showing of Fig. 4 from which it is seen that the tool presents a smooth bearing face at a point diametrically opposite the scraping lip 5'. It is the provision of such a bearing face characterized by the absence of any obstruction to a free riding travel over the surface of the cake, conjunctively with the shear-developing helix of the reaming lip, and the complementing expedient of producing a reaming twist through the application of a tangential force working to the immediate rear of the lip which is responsible for the extreme ease with which the tool may be used to dress out a tobacco chamber. Also acting to further the efficiency of the reamer is the fact of the sheet metal from which the blank for the reamer is stamped providing such a resiliency in the produced tool as to permit the reaming lip to yield slightly upon contacting a particularly hard portion of carbon cake, and in consequence preclude the development of the expansive pressure condition which, in non-yielding reamers, results not only in an objectionable cracking of the cake but in many instances of the bowl itself. It should be considered, however, that each such feature or a functional counterpart very probably might find independent utility, and it is to be therefore understood that the hereto annexed claims are to be interpreted with only such limitations as are expressly written into the same.

What I claim, is:

1. A reamer for a tobacco-pipe comprising a sheet metal body of a shape peripherally corresponding to the chamber of a pipe bowl and having a longitudinal bore and a longitudinal slot,

and with the ends of said body which lie at opposite sides of said slot extending inwardly from a true concentric and terminating in spaced relation to define a clear throat therebetween, the terminal edge of one of said ends occupying the line of a steep helix, and a reaming lip extending outwardly from said terminal edge.

2. A tobacco-pipe reamer according to claim 1 having an upwardly extending integral ear which, to receive the fingers of the operator in imparting a reaming twist, is disposed approximately tangent to the reamer proper in immediate following relation to the lip.

3. A reamer for a tobacco-pipe comprising a sheet metal body of a shape peripherally resembling a truncated cone and having a longitudinal bore and a longitudinal slot, and with the ends of said body which lie at opposite sides of said slot extending inwardly from a true concentric

and terminating in spaced relation to define a clear throat therebetween, the terminal edge of one of said ends occupying the line of a steep helix, and a reaming lip extending outwardly from said terminal edge.

4. A reamer for a tobacco-pipe comprising a sheet metal body of a shape peripherally corresponding to the chamber of a pipe bowl and having a longitudinal bore and a longitudinal slot, and with the ends of said body which lie at opposite sides of said slot terminating in spaced relation to define a clear throat from the lower to the upper limits of the reamer, one of said ends extending inwardly from a true concentric and having its terminal edge disposed to occupy the line of a steep helix, and a reaming lip extending outwardly from said terminal edge.

PAUL A. SHOUDY.
